W. P. MURPHY,
DOOR STRUCTURE FOR SHEET METAL CAR ENDS AND THE LIKE.
APPLICATION FILED MAR. 5, 1912.

Patented Aug. 8, 1916.

UNITED STATES PATENT OFFICE.

WALTER P. MURPHY, OF CHICAGO, ILLINOIS.

DOOR STRUCTURE FOR SHEET-METAL CAR ENDS AND THE LIKE.

1,193,915.

Specification of Letters Patent.

Patented Aug. 8, 1916.

Application filed March 5, 1912. Serial No. 301,785.

To all whom it may concern:

Be it known that I, WALTER P. MURPHY, a citizen of the United States, residing at Chicago, in the county of Cook and State of Illinois, have invented certain new and useful Improvements in Door Structures for Sheet-Metal Car Ends and the like, of which the following is a specification.

My invention relates to railway cars and has for its object to provide a novel door structure that may be advantageously employed when the car is to be provided with sheet metal ends, instead of the usual wooden ends, and end doors are required.

It has been proposed to furnish box cars, for example, with end structures made of sheet metal instead of wood and to form the sheet or sheets of metal constituting the end with corrugations to strengthen and rigidify the structure. An end structure of this character is shown in the patent to Walter P. Murphy and Vinton E. Sisson, No. 1,031,571, granted July 2, 1912. An objection to construction box cars with sheet metal ends has been that certain railroads require their box cars to have end doors as well as the usual side doors, and the piercing of the sheet metal structure with openings of a size to meet the requirements tends to weaken such structures and make them unfit for the hard usage to which railway cars are subjected. The purpose of corrugating the sheet metal end structure, or forming the same with ribs, particularly when these corrugations or ribs, as is preferable, extend from side to side or from top to bottom of the end, is to transmit stresses to the framework of the car. When the end is pierced by a door opening the corrugations or ribs which are intercepted by the opening of course fail to fulfil this function and are practically useless.

My invention provides a door structure (by which term I mean to include the door and also the devices and constructions on the end with which the door is engaged) of such a character that the car end is not materially weakened because of the opening formed therein.

The invention has for a further object to provide a door which can be securely fastened in place, readily removed when desired, and which, when in place, will form a perfectly waterproof closure for the door opening.

The invention is illustrated in a preferred

embodiment in the accompanying drawing, wherein—

Figure 1 shows, in elevation, the lower portion of a sheet metal car end furnished with a door embodying my invention; Fig. 2 is a fragmentary sectional view taken on line 2—2 of Fig. 1, looking in the direction of the arrows but on an enlarged scale, and Fig. 3 is a similar view taken on line 3—3 of Fig. 1 looking in the direction of the arrows.

Like characters of reference indicate like parts in the several figures of the drawing.

Referring to the drawing, 10 designates a sheet of metal forming the car end, or at least the lower part of the same. It is secured in any suitable manner to the corner posts 11 and the end sill 12, assuming the car to be a wooden box car of ordinary construction.

It will be understood that my invention is not concerned with the general structure of the car or the means employed for securing the sheet metal end to the other parts of the car.

The sheet metal end 10 is shown as formed with the corrugations or ribs 13 which preferably, but not necessarily, run horizontally of the sheet and extend from side to side of the same. The sheet 10 is pierced with a door opening 14 of any desired configuration, a circular form being preferred. The corrugations intercepted by the opening terminate close thereto and the sheet is provided with an outstanding flange 15 surrounding the opening and preferably formed integral with the sheet. By this arrangement the stresses exerted on the intercepted corrugations or ribs are transmitted around the opening through the circular flange so that the weakening effect of piercing the sheet is minimized. The door and its fastening devices are constructed and arranged to further carry out this same idea.

When the door is secured in its place over the door opening it forms a rigid structure with the car end, the end being, to all intents and purposes, as strong as if no opening had been made in it. The door preferably consists of a sheet metal cap 16 formed with a flange 17 which overlaps the flange 15 and provided with the lining or filler 18 made of wood or other relatively soft and compressible material. The filler 18 bears on the edge of flange 15. On opposite sides of the door opening are the studs

19, 20 mounted on plates 21 riveted to the sheet 10. A strap or bar 22 extends across the door. The ends of the strap are formed with the slots 23. The stud 19 preferably 5 has a head 24 and is put through the slot 23 in one end of the bar before being secured to its plate 21. The slots 23, or at least one of them, are elongated so that after the door has been closed the free end of bar 22 may 10 be slipped over the end of the stud 20. The studs 19 and 20 are provided with the nuts 25 by means of which the bar 22 may be made to force or clamp the door against the flange 15. The door may or may not be 15 secured to the bar 22 as may be deemed desirable.

While I have described my invention in the preferred embodiment it will be readily understood that some modifications thereof 20 might be made without departure from the invention. Therefore I do not limit myself to the particulars of construction described and shown except so far as the same are made specific limitations in certain of the 25 claims hereof, my purpose being to claim both broadly and narrowly whatever patentable novelty my door structure may possess in view of the state of the prior art.

I claim:

- 30 1. The combination with a sheet metal wall structure formed with corrugations, with a circular door opening intercepting one or more of said corrugations and with a circular depression around said opening 35 providing an outstanding flange, of a door formed with an inturned rim which overlaps said flange and provided with a relatively compressible lining, which bears against said flange, a strap adapted to extend diametrically across said door, and means for securing the ends of said strap to an intercepted corrugation on opposite sides of said opening so as to press the door 40 against said flange.
- 45 2. The combination with a sheet metal wall structure formed with corrugations and with a door opening intercepting one or more of said corrugations, of an outwardly extending continuous flange on said structure surrounding the opening therein arranged to transmit stresses around the opening, a door which bears against said flange and closes the opening, a strap extending across the door, and means for securing the 55 ends of the strap to said sheet metal wall structure.
3. The combination with a sheet metal wall structure formed with corrugations and with a door opening intercepting one or

more of said corrugations, of a continuous flange on said structure surrounding the opening therein and arranged to transmit stresses around said opening, a door which bears against said end structure closing the opening therein, a strap extending across the door parallel with said corrugations, and means for securing the ends of the strap to an intercepted corrugation on opposite sides of said opening so as to press said door against said wall structure.

4. The combination with a sheet metal wall structure formed with corrugations and with a circular door opening intercepting one or more of said corrugations, and provided with an outwardly extending, circumferential flange around said opening, of a door provided with an inturned rim which overlaps said flange, a strap extending across the door, and means for securing the ends of said strap to said sheet metal wall 80 structure so as to cause said door to be pressed against said flange.

5. The combination of a corrugated sheet of metal having an opening formed therein intercepting corrugations thereof, a continuous flange struck up in said sheet about said opening, a door having a continuous flange fitting closely about said opening flange, and means for removably securing said door over the opening.

6. An end structure for cars comprising a flat, corrugated sheet metal panel adapted to be secured for support to the frame of a car and provided at a place remote from its points of support with an aperture which 95 intercepts certain of the corrugations, a continuous flange formed in the panel about said aperture, a flanged door for the aperture, there being a telescopic engagement between said aperture and door flanges, and 100 means for maintaining said engagement.

7. An end structure for cars comprising a flat, corrugated sheet metal panel adapted to be secured for support to the frame of a car and provided at a place remote from its points of support with a circular aperture which intercepts certain of the corrugations, a continuous circular flange formed in the panel about said aperture, a circularly flanged door for the aperture, there being 105 a telescopic engagement between said aperture and door flanges, and means for maintaining said engagement.

WALTER P. MURPHY.
